UNITED STATES PATENT OFFICE

THOMAS A. FARMER, OF DUBACH, LOUISIANA, ASSIGNOR OF ONE-THIRD TO CYRUS E. MILLER AND ONE-THIRD TO WILLIAM R. MADDEN, BOTH OF DUBACH, LOUISIANA

WRENCH

Application filed December 31, 1928. Serial No. 329,387.

This invention relates to wrenches and more particularly to wrenches of the type generally employed on round work such as pipes and the like.

5 One of the primary objects of this invention is to provide a pipe wrench having an adjustable jaw movable toward and away from a stationary jaw with novel means for permitting the adjusting of the movable jaw 10 without the necessity of the employance of a feed nut, screw, or the like.

Another salient feature of the invention is to provide a wrench in which the movable jaw can be quickly and conveniently moved 15 to an initial work engaging position and which will tightly grip the work as pressure is applied to the handle thereof in a pre-determined direction, movement of the handle in the opposite direction tending to loosen the jaws of the wrench from engagement with the work.

A further object of the invention is to provide a quick adjustable wrench embodying a movable jaw provided with a shank slide- 25 able over the main shank of the wrench having a right angular extension slidably mounted in a guide-way in the main shank, the main shank carrying a protected rack bar on each side of the guide way, the extension being provided with a pawl engaging the rack bars, the main shank also being provided with a novel guide for said pawl.

A further object of the invention is the 35 provision of novel means for constructing the main shank and for associating the rack bar and the rigid jaw therewith.

A still further object of the invention is to provide a wrench of the above character, which will be durable and efficient in use, 40 one that will be simple and easy to manufacture, and one which can be placed upon the market at a reasonable cost.

With these and other objects in view, the 45 invention consists in the novel construction, arrangement and formation of parts, as will be hereinafter more specifically described, claimed, and illustrated in the accompanying drawing, in which drawing:—

50 Figure 1 is a side elevation of the im-

proved wrench showing the movable jaw in an adjusted position.

Figure 2 is an edge elevation of the wrench.

Figure 3 is a fragmentary longitudinal section through my improved wrench. 55

Figure 4 is a transverse section through the wrench taken on the line 4—4 of Figure 3, looking in the direction of the arrows, and

Figure 5 is a fragmentary perspective view 60 of the inner end of the shank of the movable jaw showing the extension formed thereon and the locking pawl or jaw for connection therewith, the pawl being shown removed from the extension. 65

Referring to the drawing in detail, wherein similar reference characters designate corresponding parts throughout the several views, the letter A generally indicates my improved wrench which comprises a shank 10 having a handle 11 formed on the outer end thereof. This handle 11 can have detachably associated therewith on the opposite sides thereof suitable hand grips 12. The shank 10 is formed in a novel manner, 70 in accordance with my invention and I prefer to build this shank of separate sections, in order to facilitate the easy assembling of the parts and to permit replacement to be made when parts become worn. 75

The shank 10 at its outer end is provided with an extension 13 which extends parallel to the body portion of the shank, but at one side of the longitudinal axis thereof. The shank inward of the extension 13 is provided 80 with a slot 14, for a purpose, which will be later described.

The extension 13 of the shank and the body portion of the shank supports a rigid jaw face 15 which is provided with gripping teeth 16 which are preferably arranged on the arc of a circle. The inner end of the jaw face 15 is provided with an inwardly directed attaching plate or lug 17 which is fitted within a notch 18 formed in the outer end of the extension 13 of the shank. The outer end of the jaw face 15 is provided with a retaining plate 19 which extends in spaced parallel relation to the extension and this plate engages and abuts the body por- 90

100

tion of the shank. Received in the slot 14 is the inner end of rack bar 20 which extends along the entire face of the extension 13 and the forward end of the rack bar engages the 5 inner face of the jaw 15.

Suitable securing screws 21 are extended through the body portion of the shank, the inner end of the rack bar 20, and the inner end of the plate 19 and through the lug 17, extension 13, and plate 19 adjacent to the 10 outer or forward end thereof. The outer or forward end of the rack bar is preferably enlarged to provide an abutment block 22 which engages the plate 19.

15 Both the extension 13 and the rack bar 20 are provided with slots 23 for a purpose which will be later brought out. It is to be noted that the slot defines a guide-way and that the toothed portion of the rack bar 20 20 is spaced from the plate 19 defining a second guide-way 24 which extends at right angles to the slot or guide-way 23, and these slots communicate with one another.

Movable toward and away from the rigid 25 jaw 15 is a movable jaw 30, which jaw is provided with an inner working face 31 having gripping teeth, which are also preferably arranged on the arc of a circle. This movable jaw 30 is provided with an inwardly 30 directed shank 32 which slides along the outer face of the extension 13 of the shank 10. The inner end of the movable jaw shank 32 is provided with an inwardly directed substantially right angularly disposed arm 33, which passes through the slots 23. The inner face of the movable jaw shank 32 at its lower end thereof is arcuated to provide a fulcrum 34 for engaging the extension 13. Likewise the end of the arm 33 is provided 40 with an arcuate face 35, which is adapted to engage the inner face of the plate 19 and the inner face of this plate is preferably provided with a groove or guide channel 36 for receiving the end of the arm 33 when 45 the arm is swung on the fulcrum 34.

This arm 33 carries a pawl or dog 37 which is in the nature of a transversely extending pin, said pawl or dog being disposed through an opening 38, of the same shape as the trans- 50 verse configuration of the pawl or dog, formed in the arm 33. It is to be noted that the pawl or dog has formed on the body portion thereof the longitudinally extending tooth 39 which is adapted to engage the teeth 55 of the rack bar 20. The jaw 30 is preferably connected to its shank 32 by means of a pivot pin 40, whereby the movable jaw will have a slight rocking movement on its shank and relative to the rigid jaw 15. This also allows 60 the renewal of the movable jaw in case the same becomes mutilated or injured in any way.

In use of the improved wrench the movable jaw shank 32 is swung on the fulcrum 34 65 which will move the tooth 39 of the pawl or

dog 37 to allow the engagement with the teeth of the rack bar 20, after which the movable jaw 30 is moved to its initial adjusted position relative to the rigid jaw 15 and in engagement with the work. The jaw 30 is now 70 moved around the work to its working position (shown in Figures 1 and 3) and when the handle of the wrench is swung in a clockwise direction (referring to Figure 1 of the drawings) the teeth of the rigid and movable jaws 75 will grip the work and the movable jaw will be held in tight contact therewith and allow the easy turning of the work.

When it is desired to remove the wrench from the work it is merely necessary to swing the wrench in a retrograde direction, namely a counter clockwise direction and the jaw 30 will be swung away from the work and thus allow the removal of the wrench from the work.

From the foregoing description, it can be seen that I have provided a novel wrench for round work which can be quickly adjusted on the work without the use of feed nuts or screws and which will tightly grip the work 80 when in use.

Changes in details may be made without departing from the spirit or the scope of this invention, but:—

What I claim as new is:

A wrench comprising a shank consisting of a handle forming one end of the shank and an extension forming the opposite end of the shank provided with a longitudinal slot, a rack bar carried by the inner face of said extension on each side of the slot and formed independent of the extension, a rigid jaw arranged at the outer end of the section and rack bar and secured thereto, a plate carried by said rigid jaw extending in parallel relation to the shank and secured thereto inward of the rack bars, said plate forming a guard for the rack bars and defining in connection therewith a guide-way, a movable jaw, a shank for the movable jaw rockably connected therewith and slidably along the outer face of the first mentioned shank, a laterally extending arm formed on the inner end of the second mentioned shank slidably mounted in the slot and extending into the guide-way, and a pawl carried by the inner end of said arm extending transversely of the guide-way for selective engagement with the teeth of the rack bars.

In testimony whereof I affix my signature. 120
THOMAS A. FARMER.
